ADVERTISING FOLDER

Albert T. Fischer, Cleveland Heights, Ohio

Application December 6, 1934, Serial No. 756,307

8 Claims. (Cl. 229—92.1)

The present invention relates to paper novelties and more particularly to advertising folders adapted for effecting extension of representations, etc. reproduced thereon.

5 An object of the invention is the provision of an improved folder of the character referred to in which representations reproduced thereon are extended from the folder when the same is opened.

Another object of the invention is the provision 10 of a novel folder of the character referred to, which will be inexpensive to manufacture, etc.

Further objects and advantages of the present invention will be apparent to those skilled in the art to which it pertains from the following description of the preferred embodiment of the invention described with reference to the accompanying drawings, in which:

Fig. 1 is a perspective view of a folder embodying the present invention in the open position;

20 Fig. 2 is an end view of the folder as shown in Fig. 1;

Fig. 3 is a front view of the folder ready for distribution;

Fig. 4 is an end view of the folder as shown in Fig. 3; and

25 Fig. 5 is a plan view of the sheet of material from which the folder shown in Figs. 1 to 4 inclusive is made prior to being folded.

Similar reference characters designate corresponding parts throughout the several views of 30 the drawings.

The present invention is applicable to such articles as stationery, magazine pages, advertising folders, greeting cards, etc., adapted for general distribution, or for distribution through the mails, etc., and the preferred embodiment of the invention is herein illustrated and described as embodied in an advertising folder.

Referring to the drawings, Figs. 1 and 2 show 40 a folder embodying the present invention for advertising automobile tires, as it would appear to the addressee or receiver thereof upon being opened. The representations of the tires, designated in general by the reference characters 8 and 9, reproduced on the folder have been extended as the folder was opened by the resiliency in the material from which the folder was made. Fig. 5 shows the rectangular sheet of material, 45 preferably paper or cardboard, from which the folder shown in Figs. 1 to 4 inclusive was made, before the same was folded in the manner hereinafter referred to. The sheet of material is preferably first printed, etc., with the desired advertising matter, illustrations, etc., and thereafter 50 scored normal to the longitudinal axis of the sheet

to form a plurality of sections 10 to 16 inclusive by scores 17 to 22 inclusive. The section 13 is slightly wider than the section 12, and sections 14 and 15 are approximately the same width but are slightly narrower than the section 13. The 5 sheet is scored from the front at 17, 18, and 20, and from the rear at 19, 21, and 22, in any conventional manner.

The advertising material or illustrations printed or reproduced on the sheet, in the case of 10 an advertising folder such as illustrated, preferably include a representation of the article being advertised, although a representation of some other article may be employed, if desired. As previously stated, the present folder is one intended for the advertisement of automobile tires, and the advertising material printed thereon includes the two representations of tires 8 and 9 previously referred to. The representations 8 and 9 are so positioned with reference to the 20 scores, etc., that they project above and below the scores 19 and 21, respectively, which scores, it will be noted, do not extend through the representations but stop at the edge thereof, as indicated in the drawings. The score 18 also stops 25 short of the representation 8 and does not extend therethrough, for a purpose which will later be apparent. The sheet is cut along the peripheral edge of the representations 8 and 9 above the scores 19 and 21, as at 27 and 28, respectively. 30

After the sheet has been printed, scored, and cut, as indicated, it is folded along the scores 18, 19, 20, and 21 accordion-wise to produce two double folds or pleats, designated in general by the reference characters A and B in Figs. 1 and 2, 35 along the bottom of the backing or body section 16. The lower section 16 of the sheet is then folded back along the score 22 and attached to the rear of section 11 in any convenient manner, as by stapling, stitching, crimping, or the use of 40 glue, etc. Since the representations 8 and 9 above the scores 19 and 21 have not been scored and are free of the sheet above the portion thereof which forms the crests of the folds or pleats A and B, respectively, the upper ends of the representations stand up or project from the crests of the folds in the plane of the lower or front sides thereof, that is, in the planes of the sections 13 and 15 respectively. 45

The sheet is scored at the places indicated only 50 sufficiently to facilitate folding and not sufficiently to break the material of the sheet to the extent that all resiliency is removed therefrom at the scores. This, together with the fact that a plurality of thicknesses of the material is con- 55

fined between the sections 15 and 16, causes the double folds or pleats A and B to move forward from the section 11 when the flap 10 is raised, and the representations of the tires to stand in relief against the background of the folder. It will be understood that any desired advertising matter may be carried by the folder on the front of any or all of the panels 10 to 16, inclusive, and the rear of panels 10, 11, and 16. It will be apparent that any number of double folds or pleats may be employed and innumerable arrangements of representations, and also that the double folds or pleats, etc. may be at the top or at either side of the folds, as desired.

15 In preparing the folders for distribution, upper section 10, which is approximately the same size as section 11, is folded forward and secured at its free edge to the lower end of the folder in any suitable manner. If the folder is intended 20 for distribution by mail, the sending address is preferably placed on the rear side of section 10, as viewed in Fig. 5, which appears as the front side of the same section in Fig. 3.

In the application of the present invention to 25 devices other than advertising folders, such as greeting cards, for example, the representation reproduced thereon may take any desired or appropriate form, and any arrangement thereof may be employed. As has been previously stated, 30 even in the case of advertising folders the representation reproduced thereon need not necessarily be that of the article advertised.

From the foregoing description of the preferred 35 embodiment of the invention, it will be apparent that the objects of the invention have been attained and that a new and improved folder has been produced which will effect the extension of representations reproduced thereon when the same is opened. While the invention has been 40 described with reference to a rectangular advertising folder having two double folds or pleats with a like number of representations of tires thereon, numerous modifications of the construction shown and numerous applications of the invention, some of which have been heretofore referred to, will suggest themselves to those skilled 45 in the art. This application is intended to cover all variations, adaptations, and uses of the present invention that come within the knowledge and customary practice of those skilled in the art to which it pertains. I do not wish to be limited 50 to the particular construction shown which, as stated before, may be varied within the scope of this invention, and I particularly point out and claim as my invention the following:

1. A device of the character referred to comprising sheet-material having a double fold or pleat in the front thereof provided with a projection extending from the crest of said fold formed by material cut from the sheet at one side of said crest, and a portion of said material at one side of said fold or pleat being folded backward and attached to the rear of said material.

2. A device of the character referred to comprising sheet-material having a double fold or pleat in the front thereof provided with a projection extending from the crest of said fold formed by material cut from the sheet at one side of the crest of said fold, means for permanently retaining said double fold or pleat in folded condition, and a flap formed by a score in said material adapted to be folded forward over said fold or pleat, said double fold or pleat being

adapted to automatically move forward when said flap is opened.

3. A device of the character referred to comprising sheet-material having a double fold or pleat in the front thereof intermediate the ends 5 of said material, said double fold or pleat being provided with a projection extending from the crest thereof formed by material cut from the sheet at one side of said crest, the material or sheet below said fold or pleat being folded backward and attached to the rear of said sheet, and a flap at the other end of said material formed by a score therein adapted to be folded forward over said pleat.

4. A device of the character referred to comprising sheet-material having a double fold or pleat in the front thereof intermediate the ends 15 of said sheet, said double fold or pleat being provided with a projection extending from the crest thereof in the plane of one side of the fold 20 formed by material cut from the sheet at the other side of said crest, the portion of the sheet below the said fold or pleat being folded backward and attached to the rear of said sheet, and the other end of said sheet being scored to form 25 a flap adapted to be folded forward over said pleat.

5. A device of the character referred to comprising sheet-material cut and folded to provide a plurality of double folds or pleats in the front 30 thereof having projections extending from the crests of said folds formed by material cut from the sheet at one side of said crests, and a portion 35 of said material at one side of said folds or pleats being folded backward and attached to the rear 35 of said material.

6. A device of the character referred to comprising sheet-material cut and folded to provide a plurality of double folds or pleats in the front thereof having projections extending from the 40 crests of said folds formed by material cut from the sheet at one side of the crests of said folds, means for permanently retaining said double folds or pleats in folded condition, and a flap formed by a score in said material adapted to be 45 folded forward over said folds or pleats, said double folds or pleats being adapted to automatically move forward when said flap is opened.

7. A device of the character referred to comprising sheet-material cut and folded to provide 50 a plurality of double folds or pleats in the front thereof intermediate the ends of said material, said double folds or pleats having projections extending from the crests thereof formed by material cut from the sheet at one side of said 55 crests, the material or sheet below said folds or pleats being folded backward and attached to the rear of said sheet, and a flap at the other end of said sheet formed by a score in the material adapted to be folded forward over said 60 pleats.

8. A device of the character referred to comprising sheet-material having a plurality of double folds or pleats in the front thereof intermediate the ends of said sheet, said double folds 65 or pleats being provided with projections extending from the crests thereof in the plane of one side of the fold formed by material cut from the sheet at the other side of the crests, the portion of the sheet below the said folds or pleats being 70 folded backward and attached to the rear of said sheet, and the other end of said sheet being scored to form a flap adapted to be folded forward over said pleats.
